Benjamin J. Pomer
ATTORNEY

UNITED STATES PATENT OFFICE.

AARON FRANKENHEIM, OF JERSEY CITY, NEW JERSEY.

GRATE.

Application filed March 19, 1925. Serial No. 16,603.

This invention relates to grates, or grate-bars comprising the same, and its principal object is to provide a grate with improved and efficient means for burning the smallest sizes of coal, such as screenings, barley, rice, and buckwheat sizes of coal.

Other objects and advantages will herein-after appear.

In the accompanying drawings,—

Fig. 1 shows a perspective view of a portion of the grate-bar.

Fig. 2 shows a longitudinal sectional elevation of a portion of the grate-bar, taken on the line 2—2 of Fig. 1.

The grate proper preferably consists of a plurality of cast grate-bars 1, provided with suitable frames 2, longitudinally extending strengthening or reinforcing rib 3, and pivoting journals 4 for rocking or shaking the grate. Each grate-bar is provided with a series of transverse ribs 5, which support the coal, and each rib tapers downwardly in the manner shown. The ribs 5 are separated by spaces 6 of a width approximating in dimension the thickness of the ribs, and within each space 6 is located a rib 7 which tapers upwardly in the manner shown, so that the top surface 8 of each rib is near to but under the top level 9 of the ribs 5, and between each side 10 of each rib 7 and its adjoining rib 5 there is an inclined air passage-way 11, as indicated, with the walls of each passageway tapering upwardly. The ribs 5, 7 are preferably joined by reinforcing ribs 2^a, as shown in Fig. 1. The top surfaces 8 of the rib 7 and the portions of the walls 10 adjacent to said surfaces serve to support the coal at the wide spaces 6, and in the operation of this grate, the air enters through the bottom of the inclined passageways 11 at each rib 7, flows upwardly and is thereby directed into the part of the coal supported by the ribs 7, and the air thus forming two currents merges in the space 12 above the top surface 8, whereat it is admixed and is forced upwardly, due to the combined power of the two currents, through

the general coal mass in the form of an induced strong current or draft, in which manner a maximum volume of air in the form of a strong current is continually fed into the burning mass of fine compact coal, while the fine coal is at the same time fully and efficiently supported through the agency of the auxiliary ribs 7. The tapering of the walls of the passage-ways 11 serves to admit a large volume of air and direct it upwardly through the coal mass with increased force, and these inclinations furthermore serve to permit the ashes to pass out more readily upon the shaking of the grate. It will be evident that the width of the channels 11 and the height of the spaces 12 may be proportioned to the fineness and other qualities of the coal to be used.

Variations may be resorted to within the scope of the invention.

Having thus described my invention, I claim:—

1. A grate bar having a series of ribs for supporting the fuel, said ribs tapering downwardly, a rib between each adjoining pair of said first ribs, said second ribs tapering upwardly and having their tops located below the top level of said first ribs, and said second ribs serving as an additional support for the fuel.

2. A grate bar having a series of ribs for supporting the fuel, said ribs tapering downwardly, a rib between each adjoining pair of said first ribs, said second ribs tapering upwardly and having their tops located below the top level of said first ribs, said second ribs serving as an additional support for the fuel, said ribs forming an inclined air passage-way at each side of each of said second ribs, and said passage-ways merging with each other above the tops of said second ribs.

Signed at New York, in the county of New York, and State of New York, this 18th day of March, A. D. 1925.

AARON FRANKENHEIM.
